STRINGED MUSICAL INSTRUMENT

Earl F. Anderson, 264 E. Kimball,
Raymondville, Tex. 78580

Filed Jan. 24, 1967, Ser. No. 5,547

Term of patent 7 years

(Cl. D56—1)

FIG. 1

FIG. 1 is a top plan view of a stringed musical instrument showing my new design.

FIG. 2 is a side elevational view of the same, and,
FIG. 3 is a bottom plan view of the same.

The characteristic features of my design reside in the portions shown in solid lines, conventional manual controls being shown in broken lines.

I claim:

The ornamental design for a stringed musical instrument, as shown and described.
